UNITED STATES PATENT OFFICE.

SIDNEY WORMS, OF NEW ROCHELLE, NEW YORK, ASSIGNOR TO FRANKLIN KNITTING MILLS, OF NEW YORK, N. Y., A CORPORATION OF NEW YORK.

DESIGN FOR A KNITTED OR NETTED FABRIC.

58,524.

Specification for Design.

Patented July 26, 1921.

Application filed December 10, 1920. Serial No. 429,814. Term of patent 14 years.

To all whom it may concern:

Be it known that I, SIDNEY WORMS, a citizen of the United States, residing in New Rochelle, county of Westchester, and State of New York, have invented a new, original, and ornamental Design for Knitted or Netted Fabrics, of which the following is a specification, reference being had to the accompanying drawing, forming a part thereof.

The drawing is a plan view of a knitted or netted fabric showing my new design.

I claim:

The ornamental design for a knitted or netted fabric substantially as shown.

Signed at New York city, county and State of New York, this 29th day of November, 1920.

SIDNEY WORMS.
